UNITED STATES PATENT OFFICE.

CHARLES W. SMITH, OF GRAND RAPIDS, MICHIGAN.

CURTAIN PULL.

Application filed February 4, 1925. Serial No. 6,762.

This invention relates to improvements in curtain pulls and its particular objects are to provide a device of this character which will combine attractiveness of appearance and simplicity of construction.

In decorating the rooms of a house and following harmonious color schemes it has become customary to provide such fixtures and appurtenances as may be possible, of colors or combinations of colors which will correspond and harmonize with the general color effect. The curtain pulls, which depend from the end of the cord of the window curtain and serve as a convenient grip by which the curtain may be raised or lowered, are quite conspicuous and when their color is made to correspond with the color of the other decorations of the room a pleasing effect is added.

Very frequently a combination of colors is used in the general scheme and by the present invention it is possible to very easily and conveniently combine two harmonious colors in the curtain pull or if the color scheme is a monotone a single colored curtain pull may be used just as conveniently.

The means by which the color combinations may be easily obtained and also the structure which facilitates attachment of the device to the curtain cord and also provides a simple and cheaply manufactured article are more fully described in the following description and particularly pointed out in the claim, reference being had to the accompanying drawings, in which,

Fig. 1 is an elevation, partly in section, of a curtain pull embodying this invention, shown attached to a curtain cord.

Fig. 2 is an elevation of the knob member of the curtain pull.

Fig. 3 is an elevation of the handle member of the curtain pull, and

Fig. 4 shows the curtain pull operatively attached to the cord of a window curtain.

Like reference characters refer to like parts in the different figures of the drawing.

The curtain pull embodying this invention is composed of the knob member 1 and the handle member 2. The knob member is provided with a tapped hole 3 in its lower side which receives a screw portion 4 on the upper end of the handle. A small hole 5 continuing from and joining with the tapped hole 3 in the knob extends completely

through the knob to receive the end of the curtain cord 6. To attach the device to the curtain cord the two members are separated and the cord 6 passed through the hole 5 and a knot 7 tied on its lower end which is drawn up into the tapped hole 3 to retain the knob upon the cord and the handle member 2 is then screwed in place concealing the knot 7 and providing an attractive appearing grip member by which the curtain may be raised or lowered.

The two members 1 and 2 are of a shape and construction which may be readily made on automatic wood turning machinery at very small cost and they are finished by a dipping process to give them a coating of any desired color.

One of the chief advantages of the invention is that the handles and knobs may be finished in a variety of colors and, as the knobs and handles are interchangeable, a knob and handle of the same color may be used together or a knob of one color and handle of another color may be combined. Because of this feature a merchant may, by carrying in stock a relatively small quantity of knobs and handles of comparatively few different colors, readily combine knobs and handles of different colors to produce a great variety of color effects to harmonize with decorative schemes of the rooms in which they are to be used.

Although only a single design of knob and handle is illustrated in the drawing it will be obvious that the designs and shapes of both the knobs and handles may be altered and still permit the interchangeability between the knobs and handles regardless of design or color thereby adding greatly to the number of combinations which may be obtained.

I claim:

A curtain pull comprising a knob having a tapped hole in its lower side and a smaller continuation thereof extending through the upper side, said smaller hole being adapted to receive a cord with a knotted end upon which the knob is suspended, and a handle having a threaded portion to enter said tapped hole in the knob.

In testimony whereof I affix my signature.

CHARLES W. SMITH.
